EDWARD S. HORAN AND CHARLES METZLER, JR., OF CARLSTADT, NEW JERSEY

RADIATOR

Application filed May 3, 1930. Serial No. 449,596.

This invention relates to radiators.

It is among the objects of the present invention to provide a pressure responsive device for use in radiators whereby cold air within the radiator is entirely expelled through the air valve before steam strikes the valve to heat the same and close it.

A further object of the present invention is to provide a spring-urged valve within a radiator structure whereby it will be closed upon the initial admission of steam to the radiator, thus acting as a baffle to provide for the expulsion of all of the cold air within the radiator before steam strikes the air valve and closes it.

Other objects and features of the present invention will be apparent from a consideration of the following specification taken in conjunction with the accompanying drawings, in which

Figure 1 is an elevational view, partly in section, showing a radiator embodying the present invention, and

Fig. 2 is a detail view of the device of the present invention, and

Fig. 3 is a detail transverse section of the valve rod and baffle disk assembly.

Referring more particularly to the drawings, it will be seen that the present invention is applicable to various types of steam heating radiators. The radiator shown in Fig. 1 and indicated by the numeral 10, is the conventional heater type of radiator formed by a plurality of radiator sections having inter-
35 communication at their upper and lower ends. The radiator shown in Fig. 1 is supplied with steam through a supply pipe 11 and cold air is adapted to be driven from the radiator by air vent pressure through a conventional steam valve 12. The valve 12 here shown indicates the conventional type of valve which permits the free passage of cold air therethrough but which is operated in desired manner, as by thermostatic con-
40 trol, to close when steam strikes the valve.

The present invention comprises a valve or baffle disk 13 which is faced by a suitable packing material 14. The disk and packing material are mounted upon a valve rod 15 which extends therethrough, the disk and

rod being coupled by a suitable washer 16 and cotter pin 17. Mounted upon the rod 15, a base member 18 is provided, which is adapted to be seated in the normal closure plug 19 of the end section 20 of the radiator. The 55 plug is centrally bored to receive the opposite extremity 21 of the rod 15 for suitable limited movement therein, the base 18 being adapted to secure the valve assembly within the plug 19. Mounted between the base 18 and the disk 13, a coil spring 22 is provided, which, if desired, may be adjustable to vary the spring tension applied to the disk 13.

For preventing the passage of steam through the central aperture of the disk, a 65 packing member 25 is provided. The packing member 25 is formed of asbestos or equivalent rod packing material and is adapted to snugly embrace the stem 15. Its forward face abuts the rear face of the disk 70 13. The packing 25 is urged toward the disk and inwardly toward the rod 15 by a concave washer 26 which receives thereagainst the spring 22, whereby tension of the spring is applied therethrough to the disk 13. The 75 concave design of the washer 26 provides pressure at the outer edge of the washer, the line of force of the pressure being perpendicular to the surface of the washer, whereby the packing will be urged toward the stem as 80 well as toward the back of the disk. Thus a tight seal is provided which, at the same time, permits movement of the base with respect to the disk, thus to compensate for use of the device in various sizes of fittings. 85

As shown in Fig. 1, the valve assembly is preferably mounted to close the upper joining nipple 23 of the end section and one of the intermediate sections. It will be understood that the exact position of the valve 90 assembly as here shown is not essential and may be positioned between other intermediate sections if so desired.

In the operation of the device, it will be seen that steam will be supplied through the 95 pipe 11 and in the normal operation of the radiator it will pass upwardly in the first section as indicated by the arrows in Fig. 1. In the normal operation of radiators the steam will pass across through the top join- 100

ing nipples of the sections and downwardly in the end section 20 until it strikes the valve 12, thus closing the valve. In such operation it will be seen that cold air will be trapped in the various end sections below the valve 12.

5 By the use of the present invention it will be seen that the baffle or valve will direct steam downwardly in the intermediate section next the end section as indicated by the arrow, and such downwardly moving steam will drive before it the cold air. In the end section 20, the cold air will move in the direction of the arrow and will be entirely expelled through the valve 12 before steam strikes the valve.

10 In the operation of the device, it will be understood that the disk 13 and the packing 14 do not normally move from their seat against the joining nipple 23. The arrangement is such, however, that the baffle disk and the base 18 have respective movements, thus to compensate for use in various types of fittings and in fittings having different dimensions.

15 From the foregoing it will readily be seen that the present invention provides a novel, simple and improved baffle for steam radiators. It will be understood that the invention is not specifically confined to structural features as here presented, nor to the exact location of the device as here illustrated. Numerous changes, modifications, and the full use of equivalents may obviously be resorted to without departing from the spirit or scope 20 of the present invention as outlined in the appended claims. It will be particularly noted that the device is easily applied through the opening for the plug 19 and that the device may be removed or adjusted by simple removal of the plug 19.

25 What is claimed is:

1. A radiator, including a plurality of sections having intercommunication at their upper and lower ends, and pressure responsive means in the passage between the upper ends of one pair of adjacent sections, for the purpose of clearing air from the radiator.

2. A radiator, including a plurality of sections having intercommunication at their upper and lower ends, and pressure responsive means in the passage between the upper ends of one pair of adjacent sections, for the purpose of clearing air from the radiator, said means including a spring pressed axially 50 movable disk.

25 3. A radiator, including a plurality of sections having intercommunication at their upper and lower ends, a baffle member between the upper ends of one pair of adjacent sections, said baffle member being axially movable, and spring means for normally seating said baffle member against one of said sections.

4. The combination with a radiator, of a pressure responsive device having one end

thereof fitting in a recess in the radiator to thus hold the device in position, and a spring actuated valve member on the other end of the device to control a passage between two sections of the radiator, whereby the air within the radiator may be entirely expelled by directing incoming steam through the radiator in a predetermined manner.

5 The combination with a radiator, of a pressure responsive device positioned in relation to a passage between two sections of the radiator to direct steam through the radiator to expel all the air therefrom, said device member comprising a valve disk, a valve stem for supporting said disk, spring means urging said disk to seal said passage, and a support for said stem, said support comprising a disk removably receivable within the closure plug of one of said radiator sections.
